UNITED STATES PATENT OFFICE

ALBERT F. TEICHMAN AND JOHN W. THEE, OF CINCINNATI, OHIO

WATER CONTROL DEVICE

Application filed March 2, 1928. Serial No. 258,682.

This invention relates to a water control device and has for an object the provision of a device whereby an accurately measured quantity of water may be automatically delivered from a supply pipe to a tank or container and retained therein for subsequent rapid discharge into any suitable receptacle such as a mixer.

An object of the invention is to provide a water control device which may be conveniently mounted on practically any approved type of concrete mixer and one which is adapted for automatic co-operation with such mixers to the end that a predetermined quantity of water is always available for automatic discharge into the mixer when cement and aggregate material from a loading hopper are discharged into the mixer.

Another object is to provide means for the purposes stated which so facilitates the operation of properly mixing cement and aggregate material with the proper quantity of water as to encourage the use of the automatic mechanism by the operator.

Another object is to provide a device of this kind with means whereby intentional mis-use of the device may be rendered difficult and readily observed by a supervisor.

These and other objects are attained by the means described herein and disclosed in the accompanying drawings, in which:

Fig. 1 is a fragmental side elevational view of a concrete mixer having mounted thereon a water control device of the invention.

Fig. 2 is a rear elevational view of a device of the invention.

Fig. 3 is a view taken on line 3—3 of Fig. 2.

Fig. 4 is a side elevational view of a structure forming a detail of the invention and serving to synchronize and render automatic the operation of the water control device with a concrete mixer.

Fig. 5 is a view taken on line 5—5 of Fig. 1.

The device of the invention, independent of a mixer or other mechanism to which it may be attached, comprises a suitable supporting frame 10 which may be constructed of suitable spaced angle or channel members 11 from which a bracket or upright structure 12 extends. The uprights 12 may carry suit-

able cross members 13. Fulcrums or roller bearings 14 are mounted upon upwardly projecting portions of members 12 pivotally supporting a beam structure. The beam structure comprises a bar 15 having a transverse member 16 from the opposite ends of which extend arms 17. The beam structure comprising the members 15, 16 and 17 will hereafter be referred to as beam 18 upon which is adjustably mounted a weight 19. At the ends of the arms 17 of beam 18 are depending links 20 which support a tank member 21. The arms 17 are pivotally mounted on the roller bearings 14 intermediate their opposite ends, the weight 19 normally retaining the tank in a raised position. The tank 21 is preferably provided with an inclined bottom 22 having an apertured discharge tube 23 secured thereto and supplied upon its upper face with a suitable gasket member 24. Interiorly of the tank 21 are provided lugs 25 through which extend pintles 26 for hingedly mounting a valve 27. Above the discharge tube or aperture 23 and across the top of the tank are suitable transverse members 28 to the underside of which is secured a suitable bearing 29 for the end of a rod 30 which also finds a bearing at 31 in an end wall of the tank 21.

Rigidly secured to the rod 30 is an arm 32 the end of which has pivotally attached to it a link 33. The link 33 has a pivotal connection at 34 with the valve 27. Oscillation of rod 30 by means of crank handle 35 serves to lift and lower the hingedly mounted valve 27 for opening and closing discharge pipe 23.

A water supply pipe 36 is fixedly mounted adjacent the tank 21 and has a valve controlled spout 37 overhanging the tank. The valve 38 may be of the whistle valve type, provided with a weighted lever 39 with a roller 40 on its free end and adapted to normally retain the valve in closed position when lever 39 is in a lowered and unsupported position, as shown in Fig. 3. A cam 41 is fixedly mounted on rod 30 in such position that it may operate, upon movement of the rod about its axis, to abut the roller 40 and raise lever 39 to open valve 38.

However it will be noted that, because of

100

the suspension of the tank 21 upon beam 18, the tank will rise and descend bodily accordingly as the weight 19 overbalances the empty tank, or the tank, filled with water from 5 nozzle 37, overbalances the weight. The rod 30 journalled in the tank moves bodily with it and removes the cam 41 from its position wherein it holds lever 39 in a raised position with valve 38 open. From the foregoing it 10 will be noted when the tank is filled with water sufficiently to overcome the weight 19 in its adjusted position, an accurately weighed quantity of water is in the tank and the supply shut off by the descending movement of the tank.

15 The filled tank now remains ready to be almost instantly discharged upon opening of valve 27 by turning rod 30 about its axis by means of handle crank 35 (see Fig. 3).

20 When the tank is thus emptied the weight 19 again raises the tank and rod 30, but, so long as handle 35 remains in position to hold valve 27 open, cam 41 can not touch roller 40 to raise valve lever 39. Movement of 25 handle crank 35 in the opposite direction completely closes valve 27 and then opens valve 38 by means of the cam 41. The structure thus far described is of general application and may be used to advantage by manual 30 operation of handle crank 35 in many instances.

35 The simple mechanism shown in Fig. 4 may be associated with the device just described and the combined structures applied 40 to a concrete mixer so that automatic operation of the device is attained through the agency of the loading hopper as it raises to discharge cement and aggregate material into the mixer and is lowered to receive a new 45 batch of said materials.

50 As shown in Fig. 4 a pivot bar 42 having rigidly secured to it an arm 43 is provided with a pivotal bearing at 44 upon cross member 13. This bearing is substantially in alignment with the axis of rod 30 and is 55 slightly above it. Arm 43 lies directly over the handle crank 35 to which it has an anti-friction connection through yoke 45 rigidly attached to arm 43. The yoke carries a pair of spaced rollers 46 between which the handle crank 35 extends so that when the arm and handle crank are rotated about their several spaced axes the connection between the two members is retained and the movement of the handle crank 35 relative to the 60 yoke 45 takes place with a minimum of friction. From the foregoing it will be apparent that by imparting tilting movement to pivot bar 42 about its fulcrum or pivotal mounting 65 44 the handle crank 35 may be manipulated. As will be noted in Figs. 1 and 4 the pivot bar 42 has a counter-weight 47 which normally drops to adjustable stop 48 so as to dispose the arm 43 in substantially a vertical position. In this position the arm 43 holds the

70 handle crank 35 in a substantially vertical position, (see Fig. 1) so that the rod 30 and cam 41 thereon will raise the lever 39 to open the water supply valve 38. It should be noted that in this position the valve 27 is 75 tightly closed. As shown in Figs. 1 and 5 a shaft 480 is mounted in spaced bearings 49 carried by upright members 50 which form part of the supporting structure upon which loading hopper 51 is mounted. The shaft 75 480 carries a short rocker arm 52 having a roller 53 thereon adapted to be engaged by a plate 54 carried by loading hopper 51 as it moves about its pivotal mounting at 55. The loading hopper in the present embodiment 80 is power actuated in its raising and lowering movements and is controlled by means of a throttle lever or clutch lever not shown. The shaft 480 also has a long rocker arm 56 rotatable therewith by means of a pin 62 normally disposed in a slot in sleeve 64 which is integral with arm 56 so that when the hopper 51 raises and moves short rocker arm 52 through an arc, the long rocker arm 56 is lowered. An adjustable connecting link 57 85 having a suitable clevis 58 at each end which are pivotally mounted to the long rocker arm 56 and the end of pivot bar 42 respectively, serves to automatically move the arm 43 and crank handle 35 whenever the hopper 51 is 90 raised to discharge into the mixer 59. When the hopper 51 is lowered the weight 47 returns the handle crank 35 to substantially a vertical position closing the valve 27.

95 A suitable fixed discharge spout 60 has 100 its top end positioned so as to receive the discharge tube 23 of tank 21, while its opposite end is inserted in the rotating mixer drum 59 to direct the flow in any desired manner within the drum.

105 This automatic actuation of the tank may be rendered inoperative through the mechanism shown in Fig. 5 wherein handle 61 carrying pin 62 is pushed forwardly against the resistance of spring 63 so that the pin 62 110 moves out of the slot in sleeve 64 and into the connecting slot in sleeve 65. The handle 61 is then rotated to the position shown in dotted lines in Fig. 4 and the short rocker arm 52 is moved up and out of the path of the hopper 51. It should be noted that the end of handle crank 35 extends beyond the arm 43 so that when the automatic operation is thrown out as explained, it may be 115 manually controlled by the handle crank 35.

120 The operation of the device is as follows. Assuming that the water supply pipe 36 is connected with a suitable source of water supply and the parts are in position shown in Fig. 3 wherein the tank 21 has discharged 125 its contents into the spout 60. With the automatic feature in operation, the loading hopper 51 is in a raised position at such time to discharge cement and aggregate ma- 130

- terials into the mixer 59. As soon as the tank has discharged its contents the weight 19 will drop, raising the tank bodily. It should be noted that at this time the lever 35 is still in the position shown in Fig. 3 wherefore rod 30 and cam 41 are also in the position shown in that view. The valve 27 also remains open. At this time the weighted end of the pivot bar 42 is raised, being held in that position by the action of the hopper 51 through the short and long rocker arms and connecting link 57. When the hopper is lowered, weight 47 moves pivot bar 42 about its fulcrum 44 raising long rocker arm 56 by means of the connecting link 57. At this time the arm 43 moves with the pivot bar 42 and turns the rod 30 about its axis by means of the handle crank.
- 20 It should be noted that when the tank is discharged it is in an elevated position because of the counterbalance 19; therefore relative longitudinal movement takes place between the arm 43 and handle crank 35.
- 25 When the handle crank 35 is brought to vertical position it will be noted that the valve 27 will close due to the action of arm 32 and link 33 and immediately following the closing, the cam 41 will be moved about its axis to encounter the roller 40 to raise lever 39 and to open water valve 38. Water then flows through the pipe 36 into the tank 21 until the tank contains a sufficient quantity (by weight) of water to tip the beam structure 18 about its pivotal mounting at 14 so that the tank descends bodily to encounter a stop and sufficiently to remove the cam 41 from lever 39. Thus the water supply is automatically shut off.
- 30 A suitable seal, padlock, or the like (not shown) may be employed to prevent accidental or intentional movement of weight 19 from its predetermined adjustment on the graduated member 15 of beam 18. The markings or graduations 150 may indicate net units of weight of water in the tank, when tank and weight 19 attain a position of equilibrium. In this way the device may be adjusted by a supervisor or responsible employee. The water ratio theory, with which those versed in the art are thoroughly conversant, may be put into actual practice without necessitating the employment of skilled labor.
- 35 What is claimed is:
1. In a water measuring device, the combination of a bracket, a beam structure tiltably mounted thereon, a tank suspended from the beam on one side of the bracket, a counterweight on the beam on the other side of the bracket, a rod journalled in the tank, a valve controlling discharge from the tank and a water supply pipe providing water under pressure operable by rotatable movement of the rod, a cam on said
  2. In a water measuring device the combination of a tank arranged to assume an elevated position when empty and to descend when a predetermined quantity of water is received therein, a normally closed quick flow water supply valve, a valve operating cam carried by the tank and adapted to assume an operative and an inoperative position relative to the supply valve when the tank is elevated, a discharge valve in the tank and operating means for the discharge valve and connected with the cam to render said cam inoperative on the supply valve when the discharge valve is open.
  3. In a water measuring device a beam, a water tank on the beam, an adjustable weight to raise the tank and beam when the tank is empty, a water supply valve above the tank, cam means carried by the tank and movable thereon to a raised position to open the water supply valve when the tank is raised, a discharge valve in the tank and means for effecting simultaneous movement of the cam and discharge valve.
  4. The combination with a shaft having a handle crank, a pivot bar, a rigid arm on the bar, means on the bar embracing the body of the handle crank and permitting relative longitudinal movement, a counterweight on one end of the pivot bar and means for depressing the opposite end of said pivot bar for imparting arcuate movement to the handle crank.
  5. In a water measuring mechanism for concrete mixers, a beam, a water tank on the beam, means to automatically raise the beam and tank when the tank is empty, a water supply valve above the tank, cam means carried by the tank, and, when the tank is raised, movable to a position thereon to open the water supply valve, a discharge valve in the tank, interconnecting operating means for effecting simultaneous movement of the cam and discharge valve and a remote control mechanism for the operating means comprising a pivot bar, a rigid arm on the pivot bar for effecting movement of the operating means, a counterweight at one end of the pivot bar and means for depressing the opposite end of said pivot bar whereby the operating means is actuated.
  6. In combination a mixer, a beam structure fulcrumed on the mixer, a tank and counterweight on the beam on opposite sides of the fulcrum, a quick flow water supply valve mounted over the tank, a discharge valve in the tank, operating means comprising a rod journalled on the tank to actuate the valves and means comprising a pivot bar to actuate the operating means.
  7. The combination with a normal piped

water supply under pressure of a supporting bracket for attachment to concrete mixers and the like, a quick flow gravity closed valve directly connected with said piped water supply, a water tank, a beam pivoted on the supporting structure and having the tank suspending therefrom at one end, an adjustable weight on the other end of the beam, a rod journalled in the tank, a discharge valve in the bottom of the tank, means on the rod for controlling the water supply valve and the discharge valve and movable by said rod to open the discharge valve and render said means inoperative on the water supply valve, said means being further inoperative upon the water supply valve when the tank descends under the weight of water.

8. In a water measuring device for concrete mixers the combination with a source of supply of water under pressure of a quick flow gravity closed valve controlling said water supply, a pivoted beam, a water tank suspended from one end of the beam and adapted to have the water from the supply valve flow directly therein, a rod journalled in the tank, a hingedly mounted discharge valve controlling outflow from the bottom of the tank, a lever and link mechanism in the tank actuatable by the rod for opening and closing the discharge valve, a cam mounted on said rod for opening the supply valve and an arm and pivot bar cooperating with the rod for effecting remote control movement of the rod to actuate valves.

35 In testimony whereof, we have hereunto subscribed our names this 27th day of February, 1928.

CERTIFICATE OF CORRECTION.

Patent No. 1,808,385.

Granted June 2, 1931, to

ALBERT F. TEICHMAN ET AL.

It is hereby certified that error appears in the printed specification of the above numbered patent requiring correction as follows: Page 3, line 63, claim 1, beginning with the article "a" strike out all to and including line 69, and insert instead operable by rotatable movement of the rod, a cam on said rod, a water supply pipe providing water under pressure and a lever actuated quick flow water supply valve directly controlling said supply pipe and fixedly mounted above the tank and adapted to be opened by said cam; and that the said Letters Patent should be read with this correction therein that the same may conform to the record of the case in the Patent Office.

Signed and sealed this 4th day of August, A. D. 1931.

(Seal)

**Wm. A. Kinnan,
Acting Commissioner of Patents.**
